UNITED STATES PATENT OFFICE.

JOHN CAMPBELL, OF CASCADE LOCKS, OREGON.

GAGE-SQUARE.

SPECIFICATION forming part of Letters Patent No. 735,207, dated August 4, 1903.

Application filed April 23, 1903. Serial No. 153,978. (No model.)

To all whom it may concern:

Be it known that I, JOHN CAMPBELL, a citizen of the United States, residing at Cascade Locks, in the county of Wasco and State of

5 Oregon, have invented certain new and useful Improvements in Gage-Squares; and I do declare the following to be a full, clear, and exact description of the invention, such as will enable others skilled in the art to which

10 it appertains to make and use same.

This invention relates to gage-squares.

The object of the invention is to provide a square of this character which may be utilized as a gage or as a bevel square, a further 15 object being to provide a square of this character which will be simple in construction, quickly adjusted for various uses, and which can be cheaply produced.

With these and other objects in view the 20 invention consists of certain novel features of construction, combination, and arrangement of parts, as will be more fully described, and particularly pointed out in the appended claim.

25 Figure 1 is a side view of a square embodying the invention and showing in full lines the parts on one blade of the square in position for use as a gage and on the other blade in position for lengthening the blade, other positions of the gage being shown in broken lines. Fig. 2 is a vertical sectional view on the line 2 2 of Fig. 1.

In the drawings, 1 denotes a square consisting of the blades 2 and 3, through the 35 center of which are formed longitudinally-disposed slots 2^a and 3^a.

4 and 5 denotes gage members arranged upon the blades 2 and 3, respectively. The gage members are similar in construction 40 and consist of plates of considerably less width than the blades of the square, one end of said plates being curved or offset, as at 6. The plates 4 and 5 are each provided with a longitudinally-disposed slot 7, said slot extending into the curved or offset portion of the plates, as shown.

9 denotes the bolts, which are adapted to pass through the slots in the square-blades and in the gage members and are adapted

50 to receive winged clamping-nuts 10, the bolts 9 and nuts 10, in connection with the slots, permitting the gage members to be set in any desired positions.

In Fig. 1 the full-line position of the gage member 4 on the blade 2 shows the arrangement of the gage for lengthening the blades of the square. The broken-line position *a* represents the arrangement of the same when used as a vertical gage, and the broken-line position *b* shows the same arrangement of the 60 member when used as a bevel. The position of the gage member 5 on the blade 3 shows the arrangement of the same when in use as a horizontal gage, this position also illustrating how the gage might be used for gaging or 65 measuring the elements of a molding.

The gage-square as herein shown and described is particularly adapted for the use of stone-cutters, but will be found advantageous for all constructive work.

70 From the foregoing description, taken in connection with the accompanying drawings, the construction and operation of the invention will be readily understood without requiring a more extended explanation.

75 Various changes in the form, proportion, and the minor details of construction may be resorted to without departing from the principle or sacrificing any of the advantages of this invention.

80 Having thus fully described my invention, what I claim, and desire to secure by Letters Patent, is—

A square having longitudinally-slotted arms, gage-arms of less width than the arms 85 of the square, having offset inner ends and longitudinal slots, the inner ends of which are also offset, and bolts in the respective slots of the square-arms and gage-arms, to adjustably connect the latter to the former, 90 substantially as described.

In testimony whereof I have hereunto set my hand in presence of two subscribing witnesses.

JOHN CAMPBELL.
